UNITED STATES PATENT OFFICE

OSCAR W. MILLER, OF APPLETON, WISCONSIN

CAR MOVER DEVICE

Application filed January 10, 1931. Serial No. 507,889.

This invention relates to an improved car moving device.

One of the objects of the present invention is the provision of an improved car moving device which includes an improved arch link, together with an improvement in the connection between the arch link and the operating lever, whereby the arch link can be easily actuated under a heavy load, and the shoe of the device is so arranged that both the nose of the shoe and the arch link operate as a unit upon actuation of the operating lever, to facilitate the moving of a car through the engagement of the wheels thereof.

Another object of the present invention is the provision of an improved car moving device, wherein the shoe is provided with gripping members arranged in a novel manner to serve as an advantage in gripping the rail, as opposed gripping members are provided and arranged at an angle relative to each other and disposed at an angle to the longitudinal center of the shoe.

A further object of the invention is the provision of an improved car moving device, wherein the arch link is pivoted at one end of the main shoe and is provided at the other end with a slot in which a roller operates, the roller being carried by the inner end of the actuating lever and arranged adjacent the pivot point of the lever, so that when the device is used, the nose of the shoe and arch link operate as a unit to assist in turning and pushing the car wheel.

With the above and other objects in view, the invention consists in the novel features of construction, the combination and arrangement of parts hereinafter more fully set forth, pointed out in the claim and shown in the accompanying drawings wherein:

Figure 1 is a top plan view of a car moving device, constructed in accordance with my invention;

Figure 2 is a bottom plan view, with parts thereof broken away and illustrated in cross section;

Figure 3 is a detailed longitudinal sectional view;

Figure 4 is a detailed transverse section on the line 4—4 of Figure 2; and,

Figure 5 is a detailed section on the line 5—5 of Figure 3.

The shoe 1 illustrated in the accompanying drawings is provided with a transverse central portion 2 having a V-shaped recess 3 and a longitudinal recess 4. The portion 2 is provided with a tail piece 5 and detachably engaged with this tail piece 5 is the retaining plate 6, the forward end of which is disposed at an angle, as shown at 7 and inserted within the recess 4.

The V-shaped portions 3 which are formed in the central portion 2 are disposed at an angle relative to the longitudinal center of the shoe and receive therein the substantially diamond shaped gripping members 8 in cross section, one portion of which fits within each recess 3, as shown in Figures 3 and 4, while the opposing portion is engaged by the retaining plate 6 with the outer sharp edge 9 of each gripping member being extended beyond the outer surface of the plate 6 to provide a gripping surface for the entire device which will engage the rail beneath the car wheel being operated upon.

The shoe 1 tapers to a nose portion 10 and pivoted between the side portions of this nose is the forward end of the arch link 11.

The arch link 11 is provided upon its upper surface with an inclined and slightly rounded engaging surface 12, while the inner end thereof is somewhat enlarged and provided with an elongated slot 13 adapted to receive the roller 14 carried by the transverse pin 15 which is supported in the ears 16 at the inner end of the socket 17.

The socket 17 is adapted to receive the inner tapered end 18 of an operating lever, and the socket 17 is provided with a solid tapered portion 19 which has extending transversely therethrough a pivot pin 20 which also passes through the spaced bearings 21 at the rear end of the shoe.

While the shoe 1 is described as a single piece of material, it will be noted that the same includes the parallel side members 22 which are preferably integrally connected by the central part or portion 2. The plate 6 is detachably connected to the tail portion 5 of the central portion 2 by means of the clamp-

ing bolt 6', whereby it will be noted that the plate 6 can be quickly removed from its connection with the central portion so that the gripping members 8 can be reversed to displace the dull edge which projects beyond the exterior of the plate 6 with a sharper edge. From this it will be apparent that the gripping members may be reversed so that all four edges can be used at the base of the shoe 10 before it is necessary to discard these gripping members and replace them with new ones.

In Figure 2, it will be noted that the gripping members 8 are disposed at an outwardly inclined angle upon opposite sides of the longitudinal center of the central portion 2. This arrangement of these gripping members provides a very secure grip on the upper surface of the rail, while the arch link and 20 the nose of the shoe are engaged with the car wheel. Attention is directed to the fact that the relative positions of these gripping members may be reversed or they may be inclined in the direction opposite that shown 25 in Figure 2.

The device as described and illustrated is comparatively simple in construction, but the advantages obtained for engaging the device with a car wheel and operating upon a car 30 wheel, will prove quite an advantage and considerable advantage is obtained in the mounting of the lever and the arch link so that when pressure is applied to the operating lever, the nose of the shoe and the arch 35 will operate as a unit.

While I have shown and described the preferred embodiment of my invention, it will be apparent that slight changes may be made in the construction when putting the invention 40 into practice without departing from the spirit of the same or the scope of the appended claim.

I claim:

A car mover comprising a shoe having a 45 fulcrum on its lower face at a point substantially equally distant from its ends, said shoe being provided with a longitudinally extending slot from one end thereof to the other, an operating lever having its forward end received in the slot and pivotally connected to the rear end of the shoe, the forward end of the lever in advance of the pivot being provided with a longitudinal guide slot, a lift link of substantially bell crank shape received 50 within said slot, means pivotally connecting the forward end of the lift link to the forward end of the shoe, the angle portion of the lift link being arranged substantially above the fulcrum of the shoe and opposite thereto, the rear end of the lift link being provided 55 with a closed slot received within the slotted end of the lever and closely engaged by the side walls of the slot of said lever, and a transversely extending pin carried by the 60 slotted portion of the lever having an anti-

friction roller received within the closed slot of the lift link.

In testimony that I claim the foregoing I have hereunto set my hand at Appleton, in the county of Outagamie and State of Wisconsin.

OSCAR W. MILLER.
